STERILE NEEDLE HOLDER

Cecil M. Zukerman, Davenport, Iowa

Application January 7, 1947, Serial No. 720,625

2 Claims. (Cl. 206—43)

(Granted under the act of March 3, 1883, as
amended April 30, 1928; 370 O. G. 757)

1

The invention described herein may be manufactured and used by or for the Government for governmental purposes, without payment to me of any royalty.

The present invention relates to an improved apparatus for sterilizing the needles of hypodermic syringes, together with means for maintaining the sterilized needles in sterile condition ready for use. More particularly, the invention relates to improved holding means for receiving the needles of hypodermic syringes, which holding means is easy to manufacture and permits ready insertion and removal from sterilizing instrumentalities.

The holding means of the present invention permits the simultaneous sterilization of a substantial number of hypodermic needles, and enables ready manipulation of the needles in a group without disturbance of any particular needle of the group until ready for use.

The invention will be understood more readily by reference to the accompanying drawings, wherein:

Fig. 1 represents a perspective view of the elements comprising the present invention, the parts being shown separated for purposes of illustration and clarity, it being understood that, when assembled, there is provided an efficient means for maintaining sterile the illustrated battery of needles; and

Fig. 2 is a fragmentary transverse sectional elevation of the assembly of Fig. 1 in assembled relation, the view showing certain features of the improved needle holder on an enlarged scale.

Referring more particularly to the drawings, reference character A represents improved needle-receiving means for receiving and mounting a plurality of hypodermic needles adapted to be inserted with the holder into sterilizing instrumentalities, not shown. The holder A comprises a disc-like member 4 provided with a plurality of perforations for receiving hypodermic needles 6, which are to be sterilized, and which are shown as being mounted in the removable ends 8 of hypodermic syringes. The holder A is provided with as many holes as may be needed to accommodate the desired number of needles to be sterilized, and is provided with an annular apron portion 10 which depends from the disc-like portion 4, and which extends beyond the points of the needles 6, so that when the needles have been sterilized and are awaiting use, they are retained out of engagement with any non-sterile surface which might produce a contamination of the needle points.

2

The holder A is provided with an upstanding handle stud 12. This stud is adapted to receive a cover B, the cover B being provided with a hole 14 therethrough adapted to fit over the stud 12, and is also provided with releasable spring clip means 16 adapted to engage beneath flanges 18 on stud 12 for securing the cover in position over the needles held in holder A. The spring clip 16 is provided with handle loops 20 which are adapted to be engaged readily manually for opening the clip for permitting removal of the cover from the stud 12. The coiled end portion of the spring clip 16 is received in housing 22 on the upper side of the cover B, the clip 16 thereby being permanently mounted on the cover. It will be seen that the cover B is provided with a disc-like surface 24 and an upstanding annular flange 26, although this latter detail is not of great consequence, except as a means for grasping manually the cover B.

It will be seen from Fig. 2, for example, that when the cover is assembled on the holder A, the handle stud 12 projects through the hole 14 for a substantial distance and forms a handle member for enabling the entire assembly to be lifted. The stud 12 is secured to disc-like surface 4 of holder A by means of a screw 28, or the like.

For sterilizing, the cover B is placed over the holder unit A with the stud 12 of the latter projecting through hole 14 in the cover, this hole being centrally disposed relative to the cover, the cover being conveniently of the same outside diameter and area as the holder unit A, so as to cover and protect the syringe ends 8 that are mounted in the holder A. The clip 16 engages the stud 12, so that the cover B and the holder unit A may be lifted together as a unitary structure and inserted in a steam sterilizer or other sterilizing instrumentalities, not shown. When the sterilization is completed, the cover and holder unit may be lifted as a unit from the sterilizer by lifting on stud 12 as a handle member, and placed in protecting Petri dishes, or other receiving means, the complementary parts of which are indicated at 30 and 32, respectively. When inclosed in the Petri dishes, the apron or flange portion 10 maintains the needles 6 clear of the bottom of the Petri dishes, and the top edge of the cover member B is almost in engagement with the cover 32 of the Petri dishes, so that the sterilized needles can readily be transported to a convenient location of use without any danger of loss of sterility or displacement from the holder. When it is desired to use a needle, the cover 32 of the Petri dishes is removed, and the spring clip 16 released

from engagement with the stud 12 to permit the cover B to be lifted out of engagement with the syringe portions 8 to enable access to be had thereto.

It will be apparent that it is desirable to support the needles in the holder unit A sufficiently firmly to prevent accidental displacement of the needles from their respective mounting holes. To this end, the holes which receive the syringe ends 8 are formed with tapering seat portions 34 which conform substantially to the conical ends of the syringes, and which form supporting seats therefor which firmly support the needles in place. This feature is found to contribute importantly to the successful use of the holder of this invention.

It will be understood that the embodiment of the invention herein illustrated and described represents the preferred form of the holder of the present invention, but it will be apparent that various modifications of structural details may be made without departing from the spirit and scope of the invention, as will become readily suggested to one skilled in the art; and, therefore, it will be understood that it is intended and desired to embrace within the scope of this invention such modifications and changes as may be necessary to adapt it to varying conditions and uses as defined by the scope of the appended claims.

Having thus described my invention, what I claim as new and wish to secure by Letters Patent is:

1. A holder for hypodermic needles comprising, in combination, a holding unit including a substantially planar body portion provided with openings adapted to receive needle-holding portions of hypodermic syringes, annular flange means surrounding each opening and defining a supporting seat for the needle-holding portions of the syringes, an upstanding handle member projecting from the said planar body, a cover unit for the holding unit comprising a body portion having an opening therethrough to receive the handle member of the holding unit, releasable clip means mounted on the cover unit for retaining the cover unit in position, the handle

member permitting manipulation of the holding unit and cover unit together as an integral assembly for inserting the needles into sterilizing means and for removing the needles therefrom, and annular flange means depending from the planar body of the holding unit for a distance beyond the length of the needles, whereby the needles mounted in the holding unit are retained in the unit spaced from engagement with a supporting surface for the unit, thereby maintaining the said needles in sterile condition.

2. A holder assembly for holding hypodermic needles for enabling sterilizing and maintenance thereof in sterile condition, which comprises, in combination, a holding unit including a substantially planar body portion provided with openings adapted to receive needle-holding portions of hypodermic syringes, annular flange means surrounding each opening and having an inverted substantially conical configuration corresponding to the configuration of the needle-holding portions of the syringes, the said flange means defining supporting seats for the needle-holding portions of the syringes, annular flange means projecting from the planar body portion of the holding unit to a distance greater than the length of the needles and syringe portions mounted in the openings, whereby the needles, when sterilized, are maintained out of contact with any contaminating medium until ready for use, an upstanding handle member projecting from the said planar body portion, a cover unit for the holding unit comprising a planar body portion substantially commensurate in shape and area with the planar body portion of the holding unit, the said cover unit being provided with a substantially centrally disposed opening for receiving the projecting handle member of the holding unit, releasable clip means mounted on the cover unit adapted to engage the handle member extending through the said opening, thereby enabling the holding unit and the cover unit to be manipulated together as an integral assembly, and a housing for the clip means secured to the cover unit, whereby the clip means are permanently attached to the cover unit.

CECIL M. ZUKERMAN.
